Attorney

UNITED STATES PATENT OFFICE.

JAMES M. LAFLIN, OF BOISE, IDAHO.

MULTIPLE-JAW WRENCH.

Application filed September 6, 1923. Serial No. 661,225.

This invention relates to multiple jaw wrenches, and particularly to a wrench structure having a plurality of jaw portions which can be selectively brought into position for use to suit various requirements.

An object of my invention is to provide a tool of this character consisting of a rigid double end wrench having smaller single end wrenches attached on each side thereof and adapted to be swung out to the position for use, in which latter adjustment the smaller or auxiliary wrenches clear the jaws of the main wrench.

A further object resides in so constructing and mounting the parts that the wrench has four different sets of jaws and substantially twelve different angles of disposition in which the various jaws can be used.

With the above and other objects in view which will be apparent to those skilled in the art, my present invention includes certain novel features of construction and combinations of parts which will be hereinafter set forth.

25 In the drawing:

Figure 1 is a view in top plan of a wrench constructed in accordance with my present invention.

Fig. 2 is a view in edge elevation of the wrench.

Fig. 3 is a plan view of one end of the main wrench portion illustrating one setting and adjustment of one of the auxiliary wrench portions.

Fig. 4 is a view similar to Fig. 3 showing a different adjustment.

The main wrench portion or body 1 is of the rigid double-end wrench type, with the jaws 2 and 3, preferably inclined on their central axes 2' and 3', from the central axis of the body portion 1. The auxiliary wrench members 4 and 5 are provided with smaller jaws 6 and 7, and have their remaining ends pivoted on the sides of the body portion 1 by means of pivot pins or rivets 8 and 9.

The auxiliary wrench portions 4 and 5 are so mounted on the body 1 that they can be swung to overlie the body portion on the upper and lower sides and in this position will entirely clear the jaws 2 and 3, this pivotal mounting, however, being at such points on the body portion 1 that the auxiliary members 4 and 5 can be swung completely or partially around from the position shown in Figs. 1 and 2, and in this adjustment will

extend to the positions for use, as shown in Figs. 3 and 4.

It is preferable that the axes 6' and 7' extend angularly with respect to the longitudinal axes of the auxiliary members 4 and 5, and stop lugs 10 and 11 are provided on the upper and lower sides of the body portion 1 and are positioned laterally with respect to the central axis, so that when the auxiliary wrench members are swung out to the positions for use, they will be held in predetermined settings. As is shown in Figs. 3 and 4, each auxiliary wrench member can be adjusted to either of two settings with respect to the adjacent main jaw and the stop pin, and the axial angle of any one of the jaws in any of the various adjustments can be reversed by turning the wrench over.

This wrench can be made of any suitable metal, and the jaw openings might be made of any polygonal form and might be set at other angles than those illustrated. It will also be appreciated that other changes and variations can be made in the form, construction and assemblage of the parts of my improved wrench without departing from the spirit and scope of my invention.

I claim:

1. A multiple jaw wrench comprising a rigid double end wrench portion forming a supporting body and having its jaws opening angularly from the longitudinal axis of the body, a single end auxiliary wrench member having its jaw opening angularly pivoted at its remaining end on the body to be swung to a position to extend therefrom for use, and a pin on the main wrench portion forming a stop to limit movement of the auxiliary wrench member when in a position for use, said auxiliary wrench member being adapted to be swung to a position on one side of the pin to extend substantially parallel with the supporting body and to a position on the opposite side of the pin in which the auxiliary member is angularly disposed to extend from said supporting body.

2. A multiple jaw wrench comprising a rigid double end wrench portion forming a supporting body and having its jaws opening angularly from the longitudinal axis of the body, a single end auxiliary wrench member having its jaw opening angularly pivoted at its remaining end on one side of the body adjacent one of the jaws thereof, a second single end auxiliary wrench member also having its jaw opening angularly piv-

oted on the opposite side of the body adjacent the remaining jaw thereof, said auxiliary jaw members being mounted to swing adjacent the body and clear the jaws thereof when not in use and to be swung to extend from the main wrench member for use, and stops on said main wrench member adjacent the jaws thereof and offset laterally from the longitudinal axis of the supporting body, said auxiliary wrench members being

adapted to be swung to a position on one side of the pins to extend substantially parallel with the supporting body and to a position on the opposite sides of the pins in which the auxiliary members are angularly disposed ¹⁵ to extend from said supporting body.

In testimony whereof I hereunto affix my signature.

JAMES M. LAFLIN.
